UNITED STATES PATENT OFFICE.

HENRY THOMAS HENDERSON, OF SIPE SPRINGS, TEXAS.

CHURN.

SPECIFICATION forming part of Letters Patent No. 461,883, dated October 27, 1891.

Application filed February 14, 1891. Serial No. 381,460. (No model.)

To all whom it may concern:

Be it known that I, HENRY THOMAS HENDERSON, a citizen of the United States, residing at Sipe Springs, in the county of Co-
5 manche and State of Texas, have invented cer-
tain new and useful Improvements in Churns;
and I do declare the following to be a full,
clear, and exact description of the invention,
such as will enable others skilled in the art
10 to which it appertains to make and use the
same, reference being had to the accompanying
drawings, and to the letters of reference
marked thereon, which form a part of this
specification.

15 This invention relates to certain new and
useful improvements in churning; and it re-
lates more particularly to that class of churning
in which a vertical dasher is provided and
means employed whereby in operation the
20 dasher is given a reciprocating motion.

The invention has for its object to provide
a new and improved churn of this descrip-
tion, which will be cheap of construction and
serviceable in operation.

25 To these ends and to such others as the in-
vention may pertain the same consists in the
peculiar construction and in the novel com-
bination, arrangement, and adaptation of
parts, all as more fully hereinafter described,
30 shown in the accompanying drawings, and
then specifically defined in the appended
claim.

The invention is clearly illustrated in the
accompanying drawings, which, with the let-
35 ters of reference marked thereon, form a
part of this specification, like letters of ref-
erence indicating like parts throughout the
several views, and in which drawings—

Figure 1 is a perspective view of a churn
40 embodying my improvements, parts being
shown as broken away in order to better illus-
trate the construction. Fig. 2 is a top plan.

Reference now being had to the details of
45 the drawings by letter, A designates the body
of the churn, which is in all respects similar
to churning of ordinary and well-known con-
struction. The cover of the churn is pro-
vided with a platform B, through which is
50 passed loosely the vertical shaft C, to the
lower end of which is secured the block C',
from which block depend the arms or blades
C². The upper end of the vertical shaft C is

passed loosely through an opening formed
for its passage in the arched support D, which
rises from the upper face of the platform B. 55
At one side of the platform are provided
suitable standards E E, and journaled in the
upper ends of these standards is the crank-
shaft F, provided at one of its ends with an
operating-crank F'. The pitman G has one 60
of its ends sleeved upon the crank F² of the
crank-shaft F, and the opposite end of said
pitman is pivotally connected with the bar or
link H. To the upper end of the shaft C is
secured one end of the arm I, the opposite 65
end of which arm is pivotally attached to the
outer end of the link H.

The operation of the churn is simple and
readily understood. By turning the crank
F' motion will be imparted to the shaft C, and 70
the same will be given a one-fourth revolution
and returned. The pendent blades C² of
the dasher will thus be given a reciprocating
motion, which will have the effect of thor-
oughly mixing the cream, keeping the entire 75
mass of cream within the churn in a constant
agitation.

Having thus described my invention, what I
claim to be new, and desire to secure by Let-
ters Patent, is—

80 The combination of the churn-body, its plat-
form, and shaft, the said platform having a
side extension, the arched support on the top
of the platform and having a hole through
which the shaft passes, the standards on the 85
platform to one side of the center, the crank-
shaft journaled in said standards, the hori-
zontal arm I, secured at one end to the upper
end of the shaft above the arched support,
the horizontal links pivotally connected at 90
one end with the arm I and at the other end
bifurcated, the horizontal pitman G, having
one end sleeved on the crank of the crank-
shaft and at the other pivoted between the
bifurcations of the link H, and a block on the 95
dasher-shaft beneath the platform, all sub-
stantially as shown and described.

In testimony whereof I affix my signature in
presence of two witnesses.

HENRY THOMAS HENDERSON.
